UNITED STATES PATENT OFFICE

149,723

DESIGN FOR A JUG

Eva S. Zeisel, New York, N. Y., assignor to Castleton China, Incorporated, New York, N. Y., a corporation of New York

Application April 17, 1946, Serial No. 128,708

Term of patent 14 years

(Cl. D44—21)

To all whom it may concern:

Be it known that I, Eva S. Zeisel, a citizen of the United States of America, residing at New York city, in the county of New York and State of New York, have invented a new, original, and ornamental Design for a Jug, of which the following is a specification, reference being had to the accompanying drawing, forming part thereof.

Fig. 1 is a side view of a jug showing my new design,

Fig. 2 is a longitudinal cross-section, and

Fig. 3 is a top plan view thereof.

I claim:

The ornamental design for a jug, as shown.

EVA S. ZEISEL.
